UNITED STATES PATENT OFFICE.

ROY D. CURTIS, OF SAN DIEGO, CALIFORNIA.

BRUSH.

1,171,505.

Specification of Letters Patent.

Patented Feb. 15, 1916.

Application filed June 7, 1915. Serial No. 32,722.

To all whom it may concern:

Be it known that I, Roy D. CURTIS, a citizen of the United States, residing at San Diego, in the county of San Diego and State of California, have invented new and useful Improvements in Brushes, of which the following is a specification.

The present invention relates to improvements in brushes, and has for its object the provision of a device of this character including a plurality of bristle heads adapted to be removably fitted in the stock of the brush whereby the parts may be readily separated and independently cleaned when desired.

Another object of importance resides in the construction of the parts which coöperate to force the bristle heads into effective engagement with the walls of a pocket formed in the stock of the brush into which they are adapted to be fitted, while associating the parts, with a view of facilitating this operation, together with a novel manner of locking the bristle heads as a unit in the pocket.

Other objects will appear as the nature of the invention is better understood from the following description, the invention residing in the construction, combination and arrangement of parts hereinafter set forth in detail.

In the drawing forming part of this application like numerals of reference indicate similar parts in the several views and wherein:

Figure 1 is a longitudinal sectional view through the brush constructed in accordance with my invention. Fig. 2 is a top plan view with the bristles removed. Fig. 3 is a top plan view of the stock of the brush. Fig. 4 is a perspective view of the bristle heads assembled. Fig. 5 is a bottom plan view thereof. Fig. 6 is a view showing the manner of spreading the bristle heads for cleaning the same. Fig. 7 is a perspective view of one of the bristle head sections.

Referring more particularly to the drawing A designates generally a brush constructed in accordance with my invention, it being understood that any suitable material may be employed in the production of the brush, and that the latter may vary in form and dimensions.

The handle of the brush is indicated at 5 and 55 the head or stock shown at 6, the latter hav-

ing its upper surface recessed to provide a pocket 7 in which the bristle heads are adapted to be removably fitted. The front end wall of the pocket is forwardly beveled as at 8, while the rear end wall is oppositely beveled as at 9 for a portion of its height, and then cut rearwardly to provide a shoulder 10.

The bristle head as a unit comprises a plurality of elongated flat strips 11 pivotally mounted upon the rod 12, the bristles 13 being fastened thereto in any well known manner employed by brush manufacturers. The forward end of each strip is provided with a projection 16 having its under surface beveled as at 17 to provide an inclined surface 18 when the strips are assembled as shown in Fig. 4. The inclined surface 19 is adapted to coöperate with the beveled end wall 9 of the pocket 7 on insertion of the bristle head as a unit therein, so as to force the bristle head forwardly into effective engagement with the front end wall 8 of the projections 16 in alinement with the shoulder 12. Passed transversely through an opening in one side wall of the pocket 7 is a key 20 of rectangular formation in cross section adapted to be seated upon the shoulder 12 and the projections 16 to retain the bristle head as a unit positioned within the pocket 7, the free end of the key being received within a suitable recess in the opposite side wall of the pocket 7, and having its opposite end projecting a slight distance to permit the same to be grasped when it is desired to remove the bristle heads from the brush for any purpose whatever.

By reason of the construction hereinabove described, it will be manifest that the bristle heads are not only effectively held in position within the stock of the brush, but that the same may be readily removed, and that both the stock and bristle heads may be independently cleaned when desired with a view of maintaining the brush in a sanitary condition.

It is believed that from the foregoing description, the nature and advantages of the invention will be thoroughly understood without requiring a more extended explanation and therefore the same has been omitted.

What is claimed is:

1. A brush including a head recessed to provide a pocket, the end walls of said pocket being oppositely beveled, a bristle head remov-

ably fitted within said pocket and constructed to coöperate with one of said end walls for moving said bristle head into engagement with the opposite end wall, and means for locking said parts operatively associated.

5. A brush including a head recessed to provide a pocket, the end walls of said pocket being oppositely beveled, a bristle head removably fitted in said pocket and 10 comprising a plurality of separate pivotally mounted sections, each of said sections being constructed to coöperate with one of said end walls for moving said bristle head as a unit into engagement with the opposite 15 end wall, and means for locking the parts operatively associated.

2. A brush including a head recessed to provide a pocket having one end wall provided with a shoulder, a bristle head removably fitted within the pocket and comprising a plurality of separate pivotally mounted sections, each of said sections being formed with a projection at one end adapted to lie flush with said shoulder, and a transverse key passed through said pocket above 20 said projections and shoulder for

holding the bristle head positioned within the pocket.

4. A brush including a head recessed to provide a pocket, the end walls of said pocket being oppositely beveled, a shoulder formed by one of said end walls, a bristle head removably fitted within said pocket and comprising a plurality of separate pivotally mounted sections, each of said sections having a projection at one end thereof 30 constructed to coöperate with one of said end walls for moving the said bristle head as a unit into engagement with the opposite end wall, and adapted to lie flush with said shoulder in operative position, and a transverse key passed through said pocket above 35 said projections and shoulder for holding the bristle head positioned within the pocket.

40 In testimony whereof I affix my signature in presence of two witnesses.

45 ROY D. CURTIS.
